CLAIM

The ornamental design for a chair with canopy, as shown and described.

DESCRIPTION

FIG. 1 is a side elevational view of a chair with canopy showing my new design, it being understood that the other side is a mirror image;

FIG. 2 is a bottom plan view thereof;

FIG. 3 is a top plan view thereof;

FIG. 4 is a rear elevational view thereof; and,

FIG. 5 is a front elevational view thereof.
